UNITED STATES PATENT OFFICE.

GEORGE N. SIMPSON, OF CHICAGO, ILLINOIS.

CAR AND UNLOADER.

Application filed March 6, 1925. Serial No. 13,490.

To all whom it may concern:

Be it known that I, GEORGE N. SIMPSON, a citizen of the United States, residing at Chicago, in the county of Cook and State of Illinois, have invented a new and useful Improvement in Cars and Unloaders, of which the following is a specification.

This invention relates to improvements in cars and unloaders and is here shown as embodied in apparatus especially adapted for use in mining.

For example, in the method of mining where a continuous loading machine is operated in a room at the face, and material is carried from the loading machine to the room entry or stub entry by means of a shuttle car, my improved car may constitute such a shuttle car. The unloader, forming a part of my invention, may then be placed at the room or stub entry and unload the shuttle car into the regular mine cars operating in the cross entry. My improved car and unloader are especially adapted for such use, because the car may be built very low and yet carry a relatively large load of material. The unloader is also adapted to unload it quickly so that it may make another trip with very little delay.

My improved apparatus may be easily and cheaply built, will be found to be strong and durable, and rapid and efficient in operation. Other features and advantages of my invention will appear more fully as I proceed with my specification.

In that form of device embodying the features of my invention shown in the accompanying drawings, Figure 1 is a view in side elevation of the car and unloader, showing the car being unloaded, Fig. 2 is a similar view in top plan, Fig. 3 is a transverse vertical section of the car, Fig. 4 is a top plan view of the car, and Fig. 5 is a similar view in side elevation. Fig. 6 is a detail view of the latch mechanism for controlling the dumping of the car.

As shown in the drawings, the car (see Figs. 3, 4 and 5) comprises a substantially rectangular platform 10 mounted in any suitable manner on wheels 11 adapted to run on the rails 12. Fastened on the lateral edges of the platform 10 is a pair of angle irons 13 to which are attached another pair of angle irons 14. The angle irons 13 and 14 at the side edges of the platform 10 form guides for a removable body which will be described more in detail hereinafter.

15 indicates a substantially rectangular bottomless removable body resting on the horizontal flanges of the angle irons 13 on the platform 10 and lying between the angle irons 14. The body 15 is adapted for longitudinal sliding movement between the angle irons 14, 14 as will be described more in detail hereinafter. The body 15 has no bottom but when the same is in place on the platform 10, such platform 10 acts as a bottom for the body so that a load will be retained therein.

In Fig. 1 is shown the unloader adapted to unload the car. In general, this unloader comprises an inclined slide with a hole near the upper end. The car platform is of such a height that it will be flush with the lower end of the inclined slide referred to; and a short piece of inclined track is provided for the car to run up onto so that when the forward end of the platform engages the lower end of the slide, the platform of the car and the slide will be in substantial alignment. When in this position, the removable body 15 of the car is slid off of the car platform up the slide, carrying the load with it, until it comes to the hole in the slide near the top thereof. Upon reaching this hole, the material in the bottomless body falls through such hole into any desired receptacle underneath. I will now describe this construction and operation more in detail.

The unloader shown in Fig. 1 comprises an inclined slide 16 having at its side edges a pair of angle irons 17, 17 separated the same distance as the angle irons 14 on the car platform. 118, 118 indicates a pair of inclined rails having their lower ends beveled and resting on the rails 12 so that the car wheels 11 can be drawn up onto the rails 118. When the car is thus run up onto the rails 118, the forward ends of the angle irons 14 engage the lower ends of the angle irons 17 so that the angle irons 17 will form a pair of guides constituting a continuation of the guides on the car platform in which the body 15 may slide. When the car wheels 11 are up on the rails 118 as shown in Figs. 1 and 2, the car platform 10 is also in alignment with and even with the slide 16. 18 indicates a square hole in the slide 16 near the upper end thereof. In the dumping operation, the car is pulled up onto the rails 118 until the front end of the platform 10 engages the lower end of the slide 16. The car body 15 is then pulled off of the platform 10 on the

guides 14 and up along the slide 16 between the guides 17 until the hole 18 is reached and the contents discharged therethrough into any suitable receptacle below, such as 5 a mine car 19.

For the purpose of moving the car and drawing the body 15 up the slide 16, a cable 20 is attached to an eye 21 in the rear end of the body 15. This cable is an end- 10 less cable which passes from the eye 21 around a suitable pulley (not shown) in the track at the end of the travel of the car and then returns along the track to the unloader where it is wound about a drum 15 22 and then passes around a pulley 23 at the upper end of the slide 16, beyond the discharge opening 18. After passing around this pulley it returns to the eye 21. The drum 22 is adapted to be driven in 20 any convenient manner such as, for example, by a reversible motor 24. At the front end of the platform 10 there is provided a latch 25 adapted to engage the front edge of the front wall of the body 15 in order 25 to hold the same on the platform when the cable 20 is used for moving the car. As the car goes up the inclined rails 118, however, the lower end 26 of the latch 25 is engaged by a kicker 27 on the lower end of 30 the slide 16 in order to lower the latch 25 and permit the body 15 to be drawn off of the platform of the car and up the slide 16. The car is adapted to be held on the inclined rails 118 by means of a stop 35 or horn 28 so that it will remain in place at the lower end of the slide while the body is taken up the slide for the dumping and then drawn down the slide again back onto the car platform. After the body is again 40 in place, the horn 28 is released to permit the car to go away. At the rear end of the platform 10 there is provided a pair of stops 29 to prevent the car body 15 from being drawn back too far.

45 The operation is as follows. Assuming that the car body is in place on the platform and filled with material, the drum 22 is operated in order to draw the car toward the unloader. The pull is transmitted 50 by the cable 20 to the eye fastened in the body 15. The latch 25 prevents the body from being drawn off of the platform, and consequently the entire car is pulled toward the unloader. As the car reaches the un- 55 loader, it runs up on the inclined rails 118 until the platform butts against the lower end of the slide 16. At this time, the lower end 26 of the latch 25 is engaged by the kicker 27 so that the latch 25 is lowered; and the horn 28 is raised in any suitable manner, to prevent the car from running back. A continued pull on the cable 20 then slides the body 15 off of the car platform and up the slide 16 carrying the material therein with it. When the discharge 60

opening 18 is reached, the material falls therethrough out of the body 15 and into any suitable receptacle underneath, such as a mine car 19. The movement of the cable 20 is then reversed so that the body 15 is 70 drawn down the slide back on to the platform 10 until it goes against the stops 29, 29. The horn or stop 28 is then released so that the car may be drawn back to the other end of its travel to receive a new load 75 of material.

While I have shown and described certain embodiments of my invention, it is to be understood that it is capable of many modifications. Changes, therefore, in the 80 construction and arrangement may be made without departing from the spirit and scope of the invention as disclosed in the appended claims, in which it is my intention to claim all novelty inherent in my invention as broadly as possible in view of the prior art.

What I claim as new, and desire to secure by Letters Patent, is:

1. Apparatus of the character described comprising; a car having a platform with a bottomless body thereon; a slide having one end substantially on a level with the car platform and provided with a discharge opening; and means for drawing the car body off of the car platform onto said slide and over said discharge opening. 90

2. Apparatus of the character described comprising; a car having a platform with a bottomless body thereon; an inclined slide having one end substantially on a level with the car platform and provided with a discharge opening; and means for drawing the car body off of the car platform onto said slide and over said discharge opening. 100

3. In apparatus of the character described; a car comprising a platform with a pair of guides thereon, and a slidable bottomless car body on said platform between said guides; a slide having one end substantially level with said car platform and provided with a pair of guides adapted to receive said car body, said slide also having a discharge opening therein; and means for drawing the car body off of the car platform and onto said slide and between the guides thereon, to a position over said discharge opening. 110

4. Apparatus of the character described comprising; a car having a platform with a bottomless body thereon; a catch on said car adapted to hold the body on the platform; a slide having one end substantially level with the car platform and provided with a discharge opening therein; means for releasing the catch upon the car coming into position adjacent the slide; and means for drawing the body off of the car platform onto the slide to a position over the discharge opening therein. 120

5. Apparatus of the character described comprising; a car having a platform with a bottomless body thereon; a car unloader comprising a slide having one end substantially level with the car platform, and provided with a discharge opening therein; means for moving the car, comprising an endless cable attached to the same and adapted to be operated by a drum on the car
10 unloader; means on the car unloader for drawing the car to a position with the platform thereof adjacent one end of the slide; and means on the car unloader for drawing the body of the car off of the platform onto
15 the slide to a position over the discharge opening therein.

6. Apparatus of the character described comprising; a car having a platform with a bottomless body thereon; a catch on said
20 platform adapted to hold the body thereon; a car unloader comprising a slide having one end substantially level with the car plat-

form and provided with a discharge opening therein; means adapted to release said catch on the car platform upon the car platform coming to a position adjacent one end of said slide; a winding drum on the car unloader; and an endless cable attached to the car body and passing over said winding drum.

7. Apparatus of the character described comprising; a car having a platform with a bottomless body thereon; a car unloader having a slide with one end substantially on a level with said car platform and provided with a discharge opening therein; and means on the car unloader for drawing the car up to said slide and for pulling the body thereof off of said platform onto said slide to a position over the discharge opening
